UNITED STATES PATENT OFFICE.

ALBERT E. BERDON, OF DETROIT, MICHIGAN.

THROTTLE-VALVE GOVERNOR FOR MOTORS.

1,325,615.

Specification of Letters Patent. Patented Dec. 23, 1919.

Application filed November 14, 1918. Serial No. 262,492.

To all whom it may concern:

Be it known that I, ALBERT E. BERDON, a citizen of the United States, residing at Detroit, in the county of Wayne and State

5 of Michigan, have invented a certain new and useful Improvement in Throttle-Valve Governors for Motors, of which the following is a full, clear, concise, and exact description.

10 My invention relates to fluid operated motors and is of particular service in connection with internal combustion hydro-carbon engines to which, however, the invention is not to be limited. The invention has 15 for its general object the provision of improved mechanism for governing the throttle valve of a fluid operated motor. In carrying out the invention the throttle valve of the motor is provided with a co-acting valve 20 closing portion at the outlet side of the valve and at the throttle valve opening to be operatively subject to the increasing velocity of the fluid at the throttle valve opening, and automatic mechanism, which is 25 preferably a spring, for imparting opening movements to said valve upon decreasing velocity of the fluid at the throttle valve opening. I also preferably provide manual mechanism for controlling the valve.

30 In accordance with another feature of the invention I provide an abutment which limits the extent of the valve opening movement. Mechanism is desirably provided whereby this abutment may be manually 35 adjusted to effect valve closing movement in opposition to the spring, there being preferably means whereby this mechanism may be coupled with the valve to impart both opening and closing movements thereto.

40 I will explain my invention more fully by reference to the accompanying drawings showing one embodiment thereof as applied to an internal combustion hydro-carbon engine and in which drawings Figure 1 is a 45 view mainly in longitudinal section illustrating the novel portion of an engine equipment; Fig. 2 is a sectional view on line 2-2 of Fig. 1; Fig. 3 is a view, somewhat diagrammatic, illustrating the carbureter and the intake manifold of an engine between which elements the novel portion of the engine structure is disposed; Fig. 4 is an end elevation of the structure shown in Figs. 1 and 2; Fig. 5 is a sectional view on line 5-5 of Fig. 1; Fig. 6 is a sectional view on line 6-6 of Fig. 1; Fig.

7 is a sectional view on line 7-7 of Fig. 1; and Fig. 8 is a view similar to Fig. 7 showing a changed position of an element of the structure.

60

Like parts are indicated by similar characters of reference throughout the different figures.

The novel mechanism of my invention is immediately associated with the casing 65 or piping 1, 2 which is interposed between the carbureter 3 and the intake manifold 4 of an internal combustion hydro-carbon engine, this piping having an inlet portion 5 which is in immediate connection with the carbureter structure and an outlet portion 6 which is in immediate connection with the manifold. The casing portion 1 surrounds a plurality of inwardly tapering radial webs 7 which are spaced apart by inwardly tapering radial ports 8. For convenience of manufacture and assembly, the peripheral edges of these webs are joined by a ring 9 which is clamped between the casing portions 1 and 2. Said webs carry 80 a rearwardly projecting sleeve bearing 10 at their inner merging ends. The stem 11 of a throttle valve is mounted to turn in said bearing. The throttle valve is mounted upon the front end of its stem, to turn therewith, by a screw 12 and includes a plurality of blades 13 equal in number to the ports 8. The webs 7 have their front faces flat and in a single plane which is at right angles to the axis of the valve stem 11. The blades 13 are 90 of such shape with respect to the ports 8 as to be adapted to close the same and are of such shape with respect to the webs 7 intervening between the ports as to be capable of occupying positions altogether in front 95 of these webs whereby said ports may then be completely opened. The throttle valve blades 13 are desirably provided with separately formed continuations 14 shaped somewhat as are propeller blades and so disposed 100 with respect to the carbureted air or other engine operating fluid flowing from the inlet 5 to the outlet 6 as to be given turning throttle valve closing movements, the extent of such movements depending upon the velocity of the flowing engine operating fluid and the resulting impact thereof upon the impact receiving portions 14 of the valve. The continuations 14 collectively constitute a coacting valve closing portion of the throttle 110 valve disposed at the outlet side of the valve and at the throttle valve opening to be op-

eratively subject to the increasing velocity of the fluid at the throttle valve opening. The closing movements thus imparted to the throttle valve are in opposition to the coiled spring 15 that is adjusted and connected to impart opening movements to the valve upon decreasing velocity of the fluid at the throttle valve opening. This spring is preferably co-axial with the valve stem and has secured to its rear end an anchoring ring 16 provided with a pin 17 which is receivable in any one of a number of openings 18 in the casing portion 1. These openings are arranged on the arc of a circle whose center is in the axis of the spring. By changing the hole 18 that receives the pin 17, the tension or force of the spring may be adjusted. The forward end of the spring engages a pin 19 that is carried by the collar 20 which is secured to the valve stem by means of a transverse pin 21. This pin 21 projects laterally beyond the valve stem so as to have its plane of movement intercepted by an abutment or stop 22 which is normally stationary when the throttle valve is being automatically operated. When the spring 15 is free to act it serves to open the throttle valve to the position where the pin 21 engages the stop 22, this stop and pin defining the limit of rotation and opening movement which the spring may have upon the valve. In order for the spring to have full range of movement the stop 22 (constituting a part of the manual control mechanism) must be in wide open relation and the engine must be either at rest or running under full load. If the engine be running under less than its full load and with the manual control mechanism in wide open relation, the range of movement of the spring 15 will be limited by the rotative effort produced by the impact of the engine operating fluid on the co-acting valve closing portion 14 of the throttle valve. The ports should remain full open at governing speed and full load and for all speeds below that value if the load be great enough to constitute an overload that reduces the speed below governing speed. When the engine is in operation the impact of the engine operating fluid upon the valve actuating portions 14 will cause closing movements of the valve in opposition to the spring when the engine speed exceeds the governing speed.

Incidentally, the spring may and the engine operating fluid does press the valve stem 11 forwardly, on which account I constitute the collar 20 a raceway for the balls 23 of a ball bearing whose other raceway 24 is supported by the bearing 10. By this ball bearing arrangement the forward end of the spring is not obstructed in its turning movement by friction that would otherwise arise due to the forward pressure of the spring upon said collar and the pull due to atmos-

pheric pressure on the valve 14, 13. The bearing 10 desirably has a pocket 25 formed therein for receiving oil waste. This pocket is desirably provided with an angular cover 26 that leaves a slight rear portion of the pocket 25 uncovered. An oil hole 27 is provided in the casing portion 21 in proximity to the uncovered portion of the pocket 25 to permit of the insertion of the nozzle of an oil can to lubricate the bearing 10 and the valve stem 11. This oil hole may normally be closed by a threaded plug 28.

In addition to automatically imparting opening and closing movements to the throttle valve, I also provide mechanism whereby said valve may be manually controlled. Such mechanism is in actuating relation to the abutment 22 whereby this abutment may be moved toward the pin 21 in opposition to the spring 15 whereby closing movements of the valve may be manually effected directly. By reversing the movement of the abutment 22 toward its wide open position opening movements of the valve may be effected or permitted. Any suitable means may be employed for connecting the abutment 22 with the mechanism that is to turn it. I preferably mount the abutment 22 upon a short shaft 29, these two parts being desirably fixedly related as by means of a key pin 30. The shaft 29 is mounted to turn in a bearing 31 which also forms a cap for the rear end of the casing portion 1. This cap is held in assembly with the casing portion by means of a pin 32 extending through the cap and into the casing portion 1. This pin has a semi-cylindrical notch 33 that is complementary to a semi-cylindrical notch 34 in the casing 1. The bow or shackle 35 of a padlock 36, when inserted through the opening 33, 34 keeps the pin 32 in assembly with the casing portion 1. The element 26 may be in the form of a disk whose periphery engages a packing ring 26' to prevent leakage of air into the engine operating fluid conducting portion of the casing 1, 2 when the cap 31 is removed.

A lever 37 is secured to the outer end of the shaft 29 by a pin 38. A washer 39 surrounds the shaft 29 and is interposed between the cap 31 and the adjacent end of the lever 37. The lever 37 may be connected with another lever 40 that connects the lever 37 with an operating handle at a more accessible position. The cap 31 is provided with a stop 41 which is engageable by a screw 42 upon the lever 37. By turning this screw the nearly closed throttle position of the abutment 22 may be adjusted. The manual control of the valve is exercised while the engine is turning below automatically governed speed. Screw 42 and abutment 41 must be so related as to limit the closed or nearly closed position of ports to control the idling speed and the full open position need

not be controlled by an adjustable stop but by any kind of stop. The manual lever 37 serves to forcibly hold ports closed (when the motor is being started) against the governor spring and when full against the stop should permit the motor to "idle" at some safe slow speed.

In the event of breakage of the spring or other governor parts, or if it be desired temporarily to prevent the governor from automatically performing its function, I so engage the pin 21 with the abutment 22 that movement of this abutment in either direction will cause corresponding turning movement of the valve stem 11 and the throttle valve having this stem. To this end the abutment 22 has a short finger 22' forming a fork with the part of the abutment normally engaged by the pin 21, the finger 22' being normally outside of the plane of movement of this pin. When the abutment is to actuate the pin 21 and the stem 11 carrying it in both directions said abutment is moved forwardly to engage the pin 21 between the sides of the fork. This result may be accomplished by relocating the washer 39 between the base or ring portion 22² of the abutment and the adjacent portion of the cap 31, the abutment and the shaft 29 being resecured in fixed relation with each other following this rearrangement of the parts. To make this change the seal S has to be broken, indicating to the observer that such a change has been made.

35 When the engine reaches automatically governable speed, increase in such speed increases the velocity of the engine operating fluid, causing corresponding closing movement of the valve. Reduction in speed permits the spring to impart opening movements to the valve. In a constant speed engine the inflowing engine operating fluid and the spring act in opposition to suit the supply of fluid to the requirements of the engine and its load. In the preferred embodiment of the invention the area of the valve openings or ports 8 is preferably equal to the cross sectional area of the throat of the carburetor 3 if the governor happens to be used in conjunction with a carburetor.

As I have illustrated my invention, a substantially straight line primary force is derived by the impact of the engine operating fluid upon the throttle valve portions 14 for imparting varying closing movements to the valve and occasioning corresponding varying velocities of the engine operating fluid at the valve suited to the varying loads imposed on the engine operating at some fixed speed. The shape of the blade portions 14 is such that the velocity of the fluid flowing through the ports furnishes substantially straight line primary force for all throttle openings, at fixed engine speed. The secondary force furnished by the valve opening

spring 15 must substantially conform to the primary force throughout the range of throttle openings in order to secure stable governing conditions to operate the engine at constant working speed. For constant speed 70 motor government it is, neglecting friction, only necessary to oppose a primary force, which force is caused to be the resultant of the varying velocities and which force is caused to tend to decrease the throttle opening. The secondary force tends to operate to increase the throttle opening. This secondary force is substantially equal to the primary force throughout the range of throttle openings at the required governing 80 speed of the motor.

To alter the speed to be maintained by the governor the spring is placed under increased tension for increased speed and decreased tension for decreased speed, a result 85 which may be accomplished by removing the cap 31 and locating the pin 17 in a new hole 18.

While I have herein shown and particularly described the preferred embodiment of 90 the invention I do not wish to be limited to the precise details of construction shown as changes may readily be made without departing from the spirit of my invention, but having thus described my invention I 95 claim as new and desire to secure by Letters Patent the following:

1. A fluid operated motor whose throttle valve is provided with a co-acting portion located in the portion of the throttle passage in which the velocity of the fluid passing to the motor is affected by the throttle valve and enabling the valve to have closing movements imparted thereto by the impact upon such portion of the operating fluid 100 passing to the motor; a spring operating upon the valve to effect opening movements thereof upon decrease of the valve operating influence of the motor operating fluid; an abutment limiting the extent of valve 105 opening movement; mechanism whereby said abutment may be manually adjusted to effect valve closing movement in opposition to said spring; and means whereby said mechanism may be coupled with the valve to 110 impart both opening and closing movements thereto.

2. A fluid operated motor provided with a throttle valve having a co-acting valve closing portion at the outlet side of the 120 valve and at the throttle valve opening to be operatively subject to the increasing velocity of the fluid at the throttle valve opening; and automatic mechanism for imparting opening movements to said valve upon 125 decreasing velocity of the fluid at the throttle valve opening.

3. A fluid operated motor provided with a throttle valve having a co-acting valve closing portion at the outlet side of the 130

valve and at the throttle valve opening to be operatively subject to the increasing velocity of the fluid at the throttle valve opening; and a spring operating upon the valve to effect opening movements thereof upon decreasing velocity of the fluid at the throttle valve opening.

4. A fluid operated motor provided with a throttle valve having a co-acting valve closing portion at the outlet side of the valve and at the throttle valve opening to be operatively subject to the increasing velocity of the fluid at the throttle valve opening; a spring operating upon the valve to effect opening movements thereof upon decreasing velocity of the fluid at the throttle valve opening; an abutment limiting the extent of valve opening movement; and mechanism whereby said abutment may be manually adjusted to effect valve closing movement in opposition to the spring.

5. A fluid operated motor provided with a throttle valve having a co-acting valve closing portion at the outlet side of the valve and at the throttle valve opening to be operatively subject to the increasing velocity of the fluid at the throttle valve opening; a spring operating upon the valve to effect opening movements thereof upon decreasing velocity of the fluid at the throttle valve opening; an abutment limiting the extent of valve opening movement; mechanism whereby said abutment may be manually adjusted to effect valve closing movement in opposition to the spring; and means whereby said mechanism may be coupled with the valve to impart both opening and closing movements thereto.

6. A fluid operated motor provided with a throttle valve having a co-acting valve closing portion at the outlet side of the valve and at the throttle valve opening to be operatively subject to the increasing velocity of the fluid at the throttle valve opening; automatic mechanism operating upon the valve to effect opening movements thereof upon decreasing velocity of the fluid at the throttle valve opening; an abutment limiting the extent of valve opening movement; and mechanism whereby said abutment may be manually adjusted to effect valve closing movement in opposition to the spring.

7. A fluid operated motor provided with a throttle valve having a coacting valve closing portion at the outlet side of the valve and at the throttle valve opening to be operatively subject to the increasing velocity of the fluid at the throttle valve opening; automatic mechanism for imparting opening movements to said valve upon decreasing velocity of the fluid at the throttle valve opening; and manually controlled mechanism in closing relation to the valve and operating in opposition to said automatic mechanism to effect valve closing movement.

8. A fluid operated motor provided with a throttle valve having a coacting valve closing portion at the outlet side of the valve and at the throttle valve opening to be operatively subject to the increasing velocity of the fluid at the throttle valve opening; a spring operating upon the valve to effect opening movements thereof upon decreasing velocity of the fluid at the throttle valve opening; and manually controlled mechanism in closing relation to the valve and operating in opposition to said spring to effect valve closing movement.

9. A fluid operated motor provided with a throttle valve having a coacting valve closing portion at the outlet side of the valve and at the throttle valve opening to be operatively subject to the increasing velocity of the fluid at the throttle valve opening; automatic mechanism for imparting opening movements to said valve upon decreasing velocity of the fluid at the throttle valve opening; and manually controlled mechanism in closing relation to the valve.

10. A fluid operated motor provided with a throttle valve having a coacting valve closing portion at the outlet side of the valve and at the throttle valve opening to be operatively subject to the increasing velocity of the fluid at the throttle valve opening; a spring operating upon the valve to effect opening movements thereof upon decreasing velocity of the fluid at the throttle valve opening; and manually controlled mechanism in closing relation to the valve.

In witness whereof, I hereunto subscribe my name this 8th day of Nov., A. D. 1918.

ALBERT E. BERDON.
